Primary Examiner — Mitchell I. Siegel*(74) Attorney, Agent, or Firm* — Reilly Intellectual Property Law Firm(57) **CLAIM**

The ornamental design for an extendible lacrosse stick, as shown and described.

DESCRIPTION

FIG. 1 is a perspective view showing our new design; FIG. 2 is an exploded perspective view of FIG. 1;

FIG. 3 is a front view of FIG. 1;

FIG. 4 is a side view of FIG. 1;

FIG. 5 is a top view of FIG. 1;

FIG. 6 is a rear view of FIG. 1;

FIG. 7 is a bottom view of FIG. 1; and,

FIG. 8 is an opposite side view of FIG. 4.

The broken lines included in FIGS. 1-8 are for the purpose of illustrating environmental structure and form no part of the claimed design.
